UNITED STATES PATENT OFFICE.

PAUL H. JAEHNIG, OF NEWARK, NEW JERSEY.
,Y
RECEPTACLE FOR ELECTRIC LAMPS.

No. 824,021.

Specification of Letters Patent.

Patented June 19, 1906.

Application filed May 4, 1904. Serial No. 206,275.

To all whom it may concern:

Be it known that I, PAUL H. JAEHNIG, a citizen of the United States, residing at Newark, in the county of Essex and State of New Jersey, have invented certain new and useful Improvements in Receptacles for Electric Lamps; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

- 15 The present invention relates generally to improvements in electric-lamp sockets; and the invention has reference more particularly to a novel construction of weatherproof receptacles, made of porcelain or other suitable 20 similar insulating material, for the reception of electric lamps designed for various uses, and especially in the use of electric lamps in the open air and other places where the lamps are exposed to dampness and moisture.
- 25 It has been found in practice in the use of electric incandescent lamps in the open air and in other places where the lamps are exposed to dampness and moisture that difficulty has been experienced in sufficiently 30 protecting the lamp-sockets and the metal conducting and connecting parts against the deteriorating effects of moisture and dampness so injurious to the insulation and to the various metal parts and also to prevent the 35 short-circuiting between the conducting parts of the lamp and socket.
- One of the principal objects of this invention is to provide a weatherproof or moisture-proof receptacle for electric incandescent 40 lamps designed for various uses, and especially for electric signs exposed to the weather and for outside electrical decorations in general.
- Other objects of this invention are, first, to provide an insulating wall or barrier between the points of opposite polarity or between the inner metal shell or screw-socket, into which the lamp is screwed, and the center contact, thereby giving as much separation as is possible between these points of opposite polarity; second, to provide a method of construction of the center contact whereby connection between the said contact and the wire-terminal is made through the base of the receptacle to preserve the weatherproof 55 character of the said receptacle and at the same time permitting it to be secured to a suitable support by means of a central screw passed through the said center contact; third, to provide, in connection with such means of securing the receptacle in position, 60 other holes provided with supporting-screws near the ends of the receptacle; fourth, the various screw-holes may be made that they do not extend through the base of the receptacle, but terminate slightly above the lower 65 surface or base of the receptacle to provide a thin wall in each hole, which may be broken away, but which in its normal initial condition effectually closes the hole against the entrance of moisture when not to be used; fifth, to provide, in connection with the receptacle, of porcelain or the like, an arrangement of copper or other metal screw-shell for holding the lamp in said receptacle and a center contact, of copper or other suitable metal, both said 75 shell and center contact being fastened to the porcelain base of the receptacle by means of copper or other metal screws and the said parts being concealed, whereby all the said metal parts remain perfect under the action 80 of the elements of the weather; sixth, a novel and simply-constructed connection between the screw-shell and center contact of the receptacle with the terminal plates, the terminal plates having a projection or extension, 85 preferably of a rectangular or squared cross-section, extending through the base of the receptacle to the back of the same and making electrical contact with the connecting-strips in the back of the receptacle; seventh, a novel 90 means of connecting and securing the end portion of each projection or extension of a terminal plate with and to the connection-strip by means of a bifurcated or split end, forming holding fingers or prongs which may 95 be passed through a perforation in such connecting-strip or other part of the strip and being secured thereto by being bent over 100 against the strip; eighth, an improved receptacle, of porcelain or other suitable similar material, having concealed contacts or terminal plates arranged that after the receptacle is properly connected to the lead or supply wires no live metal parts are exposed to view or 105 accidental contact; ninth, to provide an arrangement of terminal plates to which the lead or supply wires can be readily soldered after being properly secured by the binding-screws provided for this purpose in the terminal plates; tenth, to provide an ar- 110

angement of covers, of porcelain or other similar material, to protect and cover up the contacts or terminal plates after connection with the supply or lead wires has been made, 5 said covers being preferably identical in shape and size, so as to be interchangeable, and being secured to the receptacle, preferably by means of screws passing through said receptacle into the base, each screw engaging a nut which is countersunk into the base of said receptacle; eleventh, to provide an arrangement of porcelain shell or holding portion of the receptacle of such shape that the portion of said shell which extends above 10 the metal screw-shell for the lamp will act as a rain cup or shedder and will tend to shed moisture away from said screw-shell, the portion being also designed to receive a rubber or other suitable gasket to thereby provide a 15 perfect waterproof connection between the porcelain shell and the lamp; twelfth, to provide a means of sealing with a suitable waterproof and insulating compound the space between the metal screw-shell and the porcelain shell or holding portion of the receptacle 20 to prevent the entrance of moisture into the space between these parts; thirteenth, to countersink the connecting-strips and screw portions in the back of the receptacle and 25 covering these countersunk parts with a waterproof insulating compound, that these live parts of the device are not exposed to the atmosphere or to accidental contact; fourteenth, to provide an improved arrangement 30 of the lead or supply wires entering the said receptacle, whereby the strain is taken up entirely by the porcelain base of the receptacle and is removed from the terminal plates and binding-screws; fifteenth, an arrangement of 35 projections or extensions upon the base of the receptacle to produce a clearance between the base of said receptacle and its supporting structure, thereby preventing the collection of moisture between the base of the receptacle 40 and its supporting structure, which would tend to impair the life of the device, the said space allowing for a free access of air back of the receptacle and keeping it perfectly dry and free from moisture at all times, and, finally, 45 50 to provide a novel design of weatherproof receptacle for the principal purposes above enumerated which is substantial, neat, and shapely and is especially adapted for protecting incandescent-lamp sockets without offering an obstruction to the light or in any way diminishing the lighting power of such lamps.

With the various objects of the present invention in view the same consists in the novel construction of weatherproof receptacle and 55 lamp-socket hereinafter more particularly set forth; and, furthermore, this invention consists in the various arrangements and combinations of devices and parts, as well as in the details of the construction of the said parts, 60 all of which will be fully described in the fol-

lowing specification, and then finally embodied in the clauses of the claim, which are appended to this specification and form an essential part of the same.

The invention is clearly illustrated in the accompanying drawings, in which —

Figure 1 is a side elevation, and Fig. 2 a top or plan view, of a receptacle and lamp-socket embodying the principles of this invention. Fig. 3 is a top or plan view of the device with the said porcelain or other suitable covers removed; and Fig. 4 is a longitudinal vertical section taken centrally through Fig. 2 of the drawings, said view being made upon an enlarged scale. Fig. 5 is a bottom view of the device, illustrating one arrangement of the projections upon the base of the receptacle, which provide for the air-space or clearance, the waterproof insulating compound having been omitted from the countersunk portions in the said base to clearly illustrate the arrangement of the connecting-strips and the ends of the screws in the countersunk nuts. Fig. 6 is a detail vertical section taken on line 6-6 in said Fig. 5 looking in the direction of the arrow x, and Fig. 7 is a similar vertical section taken on line 7-7 in said Fig. 2 of the drawings looking in the direction of the arrow y in said Fig. 2. Fig. 8 is a perspective view of one of the terminal or contact plates and its projection. Fig. 9 is a plan or top view of a receptacle and lamp-socket of a modified construction, but still embodying the leading features of my present invention. Fig. 10 is a longitudinal vertical section of the same, taken centrally through said Fig. 9; and Fig. 11 is a bottom view of the device detached from its separable base-cover, with the waterproof insulating compound omitted from the countersunk portions of said receptacle.

Similar characters of reference are employed in the above-described views to indicate corresponding parts.

Referring now to Figs. 1 to 8 of the drawings, the reference character 1 indicates the complete receptacle for an electric lamp, the same consisting, essentially, of a base 2, which is provided with an upwardly-projecting receiving and holding portion 3, in which I have arranged and secured, preferably in the manner hereinafter more particularly set forth, a metal screw socket or shell 4. The said base 2, as will be seen from the several figures of the drawings, is preferably made with a suitable arrangement of projections or foot-pieces, as 5, at the ends of the base and with a central projection 6, thus providing a clearance between the base 2 and a supporting structure to which the receptacle is to be attached, as will be clearly understood. The said central projection 6 as well as the contiguous body portion of the said base are made with a duct 7, which communicates with an enlarged open or receiving portion 8.

in the upper part of the said base, the said receiving portion 8 being in communication with the inner cylindrical part of the receiving or holding portion or shell 3, as clearly indicated 5 in Fig. 4 of the drawings. As shown more especially in said Fig. 4, the lower portion of the said duct 7 may be closed by a thin wall 9 for effectually closing the said duct 7 against the entrance of moisture when not in use, but which thin wall may readily be broken away to permit of the arrangement of a fastening-screw in said receiving portion 8 and the duct 7 and to be screwed into the supporting structure upon which the receptacle is to be fastened. Extending from the upper surface portion 10 of the said base 2 is an annular shoulder or projection 11, formed with an annular recessed portion or depression 12, in which I have arranged a center contact or ring 13, of any suitable metal, but preferably of copper. The said center contact or ring 13 is suitably secured in the said recessed portion or depression 12 by means of the two screws 14 and 15, one of which, as 25 14, is a contact-screw and has its head 16 arranged in a hole or perforation in a connecting-strip 17. The said annular shoulder or projection 11 is made to preferably extend above the upper surface of the center contact 30 or ring 13 when in place, so as to provide a suitable insulating wall or barrier between the said center contact and the metal portions of the screw socket or shell 4, within the said holding or receiving shell 3, and thereby giving as much separation between the points of opposite polarity of the parts as is possible in a receptacle designed for the purposes of my present invention. Referring now to Figs. 4 and 6 of the drawings, it 40 will be seen that the said metal screw socket or shell 4 is provided with the screw portion 18, of the usual shape, for the reception of the screw end of an incandescent lamp in the well-known manner and is provided with a 45 centrally-perforated part 19, resting upon the surface portion 10 of the base 2 and being secured in place by means of a pair of screws 20 and 21, one of which, as 20, has its lower end connected with a nut 22, suitably arranged in a socket 23 in the said base 2, and the said other screw 21, which acts as a contact-screw, extending through a duct 24 in said base 2 and being secured to a second connecting-strip 25, as illustrated in Figs. 5 and 55 6 of the drawings. The said connecting-strip 17 is arranged in a depression or countersunk portion 26, and the said connecting-strip 25 is likewise arranged in a depression or countersunk portion 27, both being formed 60 in the bottom of the said base 2, as clearly illustrated. The said base 2 is provided in its upper portions on opposite sides of the receiving or holding shell or portion 3 with suitable depressions 28 and 29, forming pockets or chambers for the arrangement in each 65 pocket or chamber of a contact or terminal plate 30. Each contact or terminal plate 30 is made with a suitable shoulder or projection 31, against which and between the head 32 of a binding-screw 33 is arranged and secured, preferably by means of solder 34, the lead or supply wire 35, each screw 33 being passed through a screw-hole 36 in each plate 30 and extending into a duct 37 in the base 2, substantially as shown. Each contact-plate 70 30 is also provided with an extension or projection 38, preferably of a square or rectangular cross-section, the said extensions or projections 38 passing through ducts 39 and 40 and connecting, respectively, with the 75 connecting-strips 17 and 25. One preferred method of positively connecting the end portions of the said projections or extensions 38 to the said connecting-strips 17 and 25 is to split the said end portions, and thereby providing suitable fingers or prongs 41, which after being passed through suitably-disposed perforations or other receiving portions connected with the respective connecting-strips 17 and 25 are bent over, substantially as illustrated in Figs. 4 and 6, to provide a secure 80 fastening and a perfect connection, as will be clearly evident. As an extra precaution these parts may be made doubly secure by the use of solder 42 for securing said fingers 85 or lugs 41 against the said connecting-strips 17 and 25, as clearly illustrated. Suitably-shaped covers 43 are arranged over each pocket or chamber 28 and 29 to protect or cover up the contact or terminal plates 30 after connection has been properly made with the wires 35, the covers 43 being also made to cover the leads of ducts 44, which extend laterally from the said pockets or chambers on opposite sides of the receptacle. 90 The said covers 43 are two in number for each receptacle and are secured to said receptacle by means of screws 45, passing through ducts 46 in the base 2, and have their ends engaging a countersunk nut 47 in the base, as represented in Figs. 5 and 7 of the drawings.

In practice the various parts of the receptacle, as well as the covers 43, are made of porcelain or other similar insulating material, while the lamp or screw socket or shell 4 and the center contact 13, the connecting-strips 17 and 25, the contact or terminal plates 30, and the various screws are all made of metal, the exposed parts arranged in the various depressions 26 and 27 and other screw-receiving sockets and ducts in the base 2 being covered over with a suitable waterproof insulating compound or cement, as 48, to prevent any exposed metal parts which 115 might otherwise be exposed to the deteriorating effects of moisture, dampness, or water due to rain and snow. A sealing, as 49, of a suitable waterproof insulating compound or cement may also be arranged in the space 120 125 130

formed by the outer cylindrical surface of the screw socket or shell 4 and the inner surface of the receiving or holding member 3 of the receptacle to prevent the entrance of moisture into the said space that these live parts of the device may not be exposed to the atmosphere or to accidental contact. The said porcelain shell or holding member 3 may be of such shape that the portion projecting 5 above the screw socket or shell 4 shall form a rain-cup or rain-shedder 50, which tends to shed moisture and rain away from the said screw-socket 4 when in use. A suitable receiver is thus also provided in which may be 10 placed a rubber or other suitable gasket to provide a perfect waterproof connection between the said porcelain receiving or holding portion 3, the metal socket or shell 4, and that portion of the lamp which is to be screwed 15 into the said socket or shell 4.

From the foregoing description it will be seen that I have produced a simply-constructed fixture or receptacle for incandescent electric lamps which is perfectly weather 20 and moisture proof and in which all live parts are thoroughly concealed, so as not to be exposed to the injurious effects of moisture and dampness or to accidental contact. Another great advantage is that, the lead-wires extending through the receptacle in the manner illustrated, the base takes up the strain from said wires, and such strain is removed from the terminal plates and the binding-screws employed with the said 25 receptacle.

In addition to the central opening or hole 7 for the reception of a fastening-screw for securing the receptacle to a supporting structure the said base 2 may be provided 30 with other screw-receiving sockets 51, as represented in Figs. 3 and 7, for the reception of fastening-screws, the said receiving-sockets 51 being closed at the bottom of the base 2 by a thin wall 52 for effectually closing each 35 socket 51 against the entrance of moisture to preserve the weatherproof feature of the device, but which walls 52 can be broken away when it is desired to employ fastening-screws with the said sockets 51.

50 In Figs. 9, 10, and 11 of the drawings I have illustrated a modification of the receptacle, the receiving or holding portion or shell 3 of the device in this case being provided at or near the top with holding lugs or 55 ears 53, formed with suitable receiving-openings 54, preferably in the form of slots, for the reception of holding screws or bolts 55 for attaching the receptacle to a metal face-plate 56 or other suitable supporting structure substantially as illustrated. Said ears or lugs 53, as has been stated, are preferably slotted to allow for variations in spacing the screw-holes in said face-plate 56. This form 60 of receptacle is designed for metal-faced electric signs and decorations, the receiving or

holding portion or shell 3 having an annular offset 57, fitted in an opening in the face-plate 56, as represented in Fig. 10, whereby the entire receptacle is concealed behind the face of the supporting structure, which not only 70 conceals the receptacle, but also all the lead-wires. With such receptacles electric signs may be constructed with a face-plate provided with variously-disposed lamp-receiving openings, and the letters and other ornamental effects thus obtained will be self-contained and will require no additional supporting structures for securing the various receptacles in position. The general construction 75 of the porcelain receptacle and the screw-socket 4 is the same as that previously described in connection with Figs. 1 to 7, inclusive; but in this case the center contact 13 is held in place by a centrally-arranged contact-screw 58, which is also connected 80 with a contact-plate 59, arranged in a recess 61 in the bottom of the base of the receptacle and provided with a binding-screw 60. Within a second recess 62 in said base is another contact-plate 63, provided with a binding-screw 64, and one of the screws 65, 90 means of which the screw socket or shell 4 is secured in position, having its lower end connected with the contact-plate 63, as clearly illustrated in said Fig. 11. The manner of attaching the lead-wires and the manner of protecting the said contact-plates 59 and 63 against moisture and accidental contact by means of an insulating compound 66 is clearly represented in Fig. 10 of the drawings. A suitable back or base plate 67 may also be secured against the lower surface of the base of the receptacle by means of screws 68, adapted to be secured in the holes 69 in the base, or the said back plate 67 may be secured in position by other suitable fastening means, as will be clearly evident. 100

I am fully aware that changes may be made in the various arrangements and combinations of the devices and parts, as well as 110 in the details of the construction of the said parts, without departing from the scope of my present invention. Hence I do not limit my invention to the exact arrangements and combinations of the devices and their parts 115 as described in the foregoing specification and as illustrated in the accompanying drawings; nor do I confine myself to the exact details of the construction of the said parts.

Having thus described my invention, what 120 I claim is—

1. An electric-lamp receptacle comprising a base and an upwardly-projecting receiving and holding portion all of insulating material integral with said base, a metal screw-socket in said holding portion, metal connections for making electrical contact, said connections being all of them arranged and concealed directly in the body of said receptacle 125 to protect them against moisture and acci- 130

- 5 dental contact, and cover-plates upon said body and at the sides of said holding portion arranged to cover some of said connections, substantially as and for the purposes set forth.
2. An electric-lamp receptacle comprising a base and an upwardly-projecting receiving and holding portion all of insulating material integral with said base, a metal screw-socket in said holding portion, metal connections for making electrical contact, said connections being all of them arranged and concealed directly in the body of said receptacle, an insulating compound arranged over the exposed portions of said connections to conceal said connections and protect them against moisture and accidental contact, and cover-plates upon said body and at the sides of said holding portion arranged to cover some of said connections, substantially as and for the purposes set forth.
3. An electric-lamp receptacle comprising a base and an upwardly-projecting receiving and holding portion all of insulating material integral with said base, and the said base being provided in its lower surface with receiving-depressions, a metal screw-socket in said holding portion, a metal connecting-strip in each receiving-depression, metal connections for making electrical contact with said strips, said connections being all of them arranged and concealed directly in the body of said receptacle, and cover-plates upon said body and at the sides of said holding portion arranged to cover some of said connections, substantially as and for the purposes set forth.
4. An electric-lamp receptacle comprising a base and an upwardly-projecting receiving and holding portion all of insulating material integral with said base, and the said base being provided in its lower surface with receiving-depressions, a metal screw-socket in said holding portion, a metal connecting-strip in each receiving-depression, metal connections for making electrical contact with said strips, said connections being all of them arranged and concealed directly in the body of the receptacle, an insulating compound arranged over said connecting-strips and the exposed portions of said connections to conceal the said strips and connections and protect them against moisture and accidental contact, and cover-plates upon said body and at the sides of said holding portion arranged to cover some of said connections, substantially as and for the purposes set forth.
5. An electric-lamp receptacle comprising a base and an upwardly-projecting receiving and holding portion all of insulating material integral with said base, and the said base being provided in its lower surface with receiving-depressions, a metal screw-socket in the said holding portion, a metal connecting-strip in each receiving-depression, metal terminal plates, a projection extending from each terminal plate, a split or bifurcated end portion on each projection secured to a connecting-strip, all arranged and concealed directly in the body of said receptacle, and cover-plates upon said body and at the sides of said holding portion arranged to cover some of said connections, substantially as and for the purposes set forth.
6. An electric-lamp receptacle comprising a base and an upwardly-projecting receiving and holding portion all of insulating material integral with said base, and the said base being provided in its lower surface with receiving-depressions, a metal screw-socket in the said holding portion, a metal connecting-strip in each receiving-depression, metal terminal plates, a projection extending from each terminal plate, a split or bifurcated end portion on each projection secured to a connecting-strip, said connections being all of them arranged and concealed directly in the body of said receptacle, an insulating compound arranged over said connecting-strips and the exposed portions of the connected parts to conceal and protect the same against moisture and accidental contact, and cover-plates upon said body and at the sides of said holding portion arranged to cover some of said connections, substantially as and for the purposes set forth.
7. An electric-lamp receptacle comprising a base and an upwardly-projecting receiving and holding portion for the reception of a lamp, said base and holding portion being integrally connected and made of insulating material, a center contact in said holding portion, and an insulating-wall integrally connected with said base and extending about the center contact to provide a barrier between the points of opposite polarity when in electric circuit, substantially as and for the purposes set forth.
8. In an electric-lamp receptacle, a base and an upwardly-projecting receiving and holding portion for the reception of a lamp, said base and holding portion being integrally connected and made of insulating material, of a ring-shaped projection integrally connected with and extending upwardly from the said base into said holding portion, the said ring-shaped projection being provided with an annular recess, and a center contact arranged in the said recess of said ring-shaped projection, and said projection forming an insulating-wall around the said center contact, substantially as and for the purposes set forth.
9. In an electric-lamp receptacle, a base and an upwardly-projecting receiving and holding portion for the reception of a lamp, said base and holding portion being integrally connected and made of insulating material, of a ring-shaped projection integrally connected with and extending upwardly from the

said base into said holding portion, the said ring-shaped projection being provided with an annular recess, and a center contact arranged in the said recess of said ring-shaped projection, said projection forming an insulating-wall around the said center contact, and the said base and said ring-shaped projection being provided with a fastening-screw-receiving means, substantially as and for the purposes set forth.

10. In an electric-lamp receptacle, the combination, with a base and an upwardly-projecting receiving and holding portion for the reception of a lamp, both the said base and holding portion being integrally connected and made of an insulating material, the said base being provided with receiving-depressions, a metal connecting-strip in each depression, a pair of terminal plates, a projection connected with each terminal plate, and a split end portion on each projection connected with a connecting-strip, said connecting-strips and terminal plates being all of them concealed in said base, and a cover-plate detachably arranged over each receiving-depression, substantially as and for the purposes set forth.

11. In an electric-lamp receptacle, the combination, with a base and an upwardly-projecting receiving and holding portion for the reception of a lamp, both the said base and holding portion being integrally connected and made of an insulating material, the said base being provided with receiving-depressions, a metal connecting-strip in each depression, a pair of terminal plates, a projection connected with each terminal plate, a split end portion on each projection connected with a connecting-strip, and a solder for securing each split portion to its connecting-strip, said connecting-strips and terminal plates being all of them concealed in said base, and a cover-plate detachably arranged over each receiving-depression, substantially as and for the purposes set forth.

12. In an electric-lamp receptacle, the combination, with a base and an upwardly-projecting receiving and holding portion for the reception of a lamp, both the said base and holding portion being integrally connected and made of an insulating material, the said base being provided with receiving-depressions, a metal connecting-strip in each depression, a pair of terminal plates, a projection connected with each terminal plate, a split end portion on each projection connected with a connecting-strip, a solder for securing each split portion to its connecting-strip, and an insulating compound arranged over said connecting-strips and the exposed portions of the connected parts to conceal and protect the same against moisture and accidental contact, said connecting-strips and terminal plates being all of them concealed in said base, and a cover-plate detachably arranged

over each receiving-depression, substantially as and for the purposes set forth.

13. An electric-lamp receptacle comprising a base and a holding portion for the reception of a lamp, both the said base and holding portion being made of an insulating material, the said base being provided with a pair of receiving-depressions in its lower surface, said base being also provided with a pair of pockets, and with a connecting-duct between each pocket and a receiving-depression, a cover arranged over each pocket, a metal connecting-strip in each receiving-depression, a terminal plate and binding-screw in each pocket with which a lead-wire extending through the pocket can be connected, a projection connected with each terminal plate, each projection extending through a duct to one of said depressions, and a split end portion on each projection connected with a connecting-strip, substantially as and for the purposes set forth.

14. An electric-lamp receptacle comprising a base and a holding portion for the reception of a lamp, both the said base and holding portion being made of an insulating material, the said base being provided with a pair of receiving-depressions in its lower surface, said base being also provided with a pair of pockets, and with a connecting-duct between each pocket and a receiving-depression, a cover arranged over each pocket, a metal connecting-strip in each receiving-depression, a terminal plate and binding-screw in each pocket with which a lead-wire extending through the pocket can be connected, a projection connected with each terminal plate, each projection extending through a duct to one of said depressions, a split end portion on each projection connected with a connecting-strip, and a solder for securing each split end portion to its connecting-strip, substantially as and for the purposes set forth.

15. An electric-lamp receptacle comprising a base and a holding portion for the reception of a lamp, both the said base and holding portion being made of an insulating material, the said base being provided with a pair of receiving-depressions in its lower surface, said base being also provided with a pair of pockets, and with a connecting-duct between each pocket and a receiving-depression, a cover arranged over each pocket, a metal connecting-strip in each receiving-depression, a terminal plate and binding-screw in each pocket with which a lead-wire extending through the pocket can be connected, a projection connected with each terminal plate, each projection extending through a duct to one of said depressions, a split end portion on each projection connected with a connecting-strip, and an insulating compound arranged over said connecting-strips and the exposed portions of the connected

parts to conceal and protect the same against moisture and accidental contact, substantially as and for the purposes set forth.

16. An electric-lamp receptacle comprising a base and a holding portion, both made from insulating material, a metal lamp-socket in said holding portion, said metal socket having a central opening, an annular projection extending from said base through the said central opening in said socket and into the said holding portion, said projection being provided with an annular recess, a center contact in said recess, said annular projection extending above the said center contact to provide an insulating-wall, a pair of fastening-screws in said base and attached to said center contact, the said base being also provided with a pair of receiving-depressions, a connecting-strip in each depression, one of said connecting-strips making contact with one of said screws, the said base being further provided with a pair of pockets and a connecting-duct between each pocket and a receiving-depression, a terminal plate in each pocket, and a projection connected with each terminal plate extending through a connecting-duct and having its free end connected with a connecting-strip, substantially as and for the purposes set forth.
17. An electric-lamp receptacle comprising a base and a holding portion, both made from insulating material, a metal lamp-

socket in said holding portion, said metal socket having a central opening, an annular projection extending from said base through the said central opening in said socket and into the said holding portion, said projection being provided with an annular recess, a center contact in said recess, said annular projection extending above the said center contact to provide an insulating-wall, a pair of fastening-screws in said base and attached to said center contact, the said base being also provided with a pair of receiving-depressions, a connecting-strip in each depression, one of said connecting-strips making contact with one of said screws, the said base being further provided with a pair of pockets and a connecting-duct between each pocket and a receiving-depression, a terminal plate in each pocket, and a projection connected with each terminal plate extending through a connecting-duct and into a receiving-depression, and a split portion forming fingers at the free end of each projection, said fingers being secured to a connecting-strip, substantially as and for the purposes set forth.

In testimony that I claim the invention set forth above I have hereunto set my hand this 27th day of April, 1904.

PAUL H. JAEHNIG.
